United States Patent Office

Des. 197,849
Patented Mar. 31, 1964

197,849

PLATE OR THE LIKE

Sara Little, New York, N.Y., assignor to Corning Glass Works, Corning, N.Y., a corporation of New York

Filed Nov. 14, 1963, Ser. No. 77,427

Term of patent 14 years

(Cl. D44—15)

The figure is a top plan view of a plate of conventional configuration showing my new design.

I claim:

The ornamental design for a plate or the like, as shown and described.
